UNITED STATES PATENT OFFICE.

FRANK FRNKA, OF GARWOOD, TEXAS.

COMBINED STOCK GUARD AND PASSWAY.

Application filed February 10, 1927. Serial No. 167,283.

The invention relates to improvements in structures adapted primarily for use in fences instead of using gates, for the purpose of permitting automobiles and other vehicles to pass from one side of the fence to the other, while preventing cattle and other stock from so passing, provision being made however, for conditioning the device, so that stock may readily pass from one side 10 of the fence to the other, whenever desired.

A somewhat similar device is shown by my U. S. Patent No. 1,616,361, of February 1st, 1927, and the present application is directed to certain distinct improvements over the 15 patented construction.

The device embodies a base frame having a plurality of spaced bars over which cattle or other stock will not walk, but a platform is provided downwardly swingable to a horizontal position whenever stock must cross the device, or when a horse-back rider or horse-drawn vehicle must pass thereover, and it is the principal object of the invention to provide novel means for holding the 20 platform in lowered position when a horse-back rider or a horse-drawn vehicle is to pass thereover, the holding means however being such that it is released by the weight of the horse or vehicle, so that the platform 25 may then again rise to its inoperative position, under the influence of a weight or equivalent means.

Another aim is to provide for holding the above-named platform-holding means against release under the influence of weight upon the platform, when a number of cattle or other stock or when a number of horse-drawn vehicles, or horse-back riders must pass thereover.

With the foregoing and minor objects in view, the invention resides in the novel subject matter hereinafter described and claimed, the description being supplemented by the accompanying drawings.

Fig. 1 is a perspective view showing the platforms in lowered position.

Fig. 2 is a perspective view showing the platforms in their normally raised positions.

Fig. 3 is a longitudinal sectional view with the platforms raised in full lines and lowered in dotted lines.

Fig. 4 is a vertical transverse sectional view on line 4-4 of Fig. 2.

Fig. 5 is a fragmentary top plan view 65 illustrating the manner in which the platforms may be positively locked against

ascent, upon passage of any weight thereover.

Fig. 6 is a fragmentary perspective view of the parts illustrated in Fig. 5. 60

In the drawings above briefly described, illustrating one advantageous form of construction, the numeral 10 designates a rectangular base frame of any desired size and proportion, which frame may be mounted in a gap of a fence 11, may span a ditch or stream, or may be otherwise located as occasion may demand, and it will of course be understood that a foundation of any desired form may be used for this frame. 65

Extending transversely of the frame 10, below the top of the latter, I dispose a number of sills 12 whose ends are secured to the parallel side bars of said frame. Supported upon these sills and extending longitudinally within the frame, with their upper edges flush with the top of the latter, are a number of spaced parallel bars 13, which bars terminate in spaced relation with the end bars of the frame 10 to provide openings 14, 70 for a purpose to appear. Brace blocks are secured upon the upper edges of the sills 12 between the longitudinal bars 13 and contact with these bars, most of said blocks (15) 75 having somewhat sharpened upper portions to prevent accumulation of dirt and the like, although some of the blocks (16) near the transverse center-line of the frame 10, have flat upper surfaces for a purpose to appear. 80

and in this connection, it will be observed 90 that two of the sills 12 are disposed near the transverse center of the frame, the space between these sills, adjacent the ends of the latter being spanned by said blocks 16. Secured upon these blocks 16 and the flush portions 95

of a number of the bars 13, are footboards 17 which are somewhat triangular, due to the preferred shaping of certain platforms hereinafter described. Extending transversely across the intermediate sills 13 100 and abutting the inner ends of the footboards 17 is a latch-supporting bar 18. Mounted upon this bar, is any desired form of latch or equivalent means for holding the above-named platforms in depressed position when desired. In the present showing, a horizontally elongated latch 19 is pivoted between its ends at 20 upon the bar 18 and may well rest with practically no friction, upon the raised central portion of a suitable 105 washer 21. This latch 19 is normally held in a position extending longitudinally of the 110

bar 18, under the influence of a cable 22, a weight 23 thereon, and a pulley 24. This pulley 24 is mounted in an appropriate opening 25 in the bar 18, the cable 22 passes over said pulley and is connected at one end with one end of the latch 19 and the other end of the cable depends from the pulley and is provided with the weight 23. The opening 25 is of such size that the weight may be upwardly drawn therethrough in case repairs or replacement of the cable are necessary, and in case this cable should break, the weight is held against excessive dropping, by a safety cable 26. Between the pulley 24 and the latch 19, the cable 22 passes through an appropriate cable-guide 27 which prevents it from jumping the pulley, when the latch is swung transversely of the bar 18, as shown in Fig. 1.

23 The particular form of latch 19 herein disclosed, is provided with a pair of projecting handles 28 at its ends, by either of which said latch may be turned to operative position, but I take this opportunity of again stating that I am not restricted to the particular form of latch herein disclosed.

23 Two platforms 29 are provided in the present disclosure, for covering the longitudinal bars 13 when desired, these platforms preferably consisting of planks suitably secured to longitudinal sills 30, which sills are secured to transverse rock shafts 31. These rock shafts have their ends mounted in appropriate bearings 32, by which they are confined to positions outwardly spaced to some extent from the ends of the sills 13, the latter being beveled as shown.

40 The sills 30 not only project in one direction from the shafts 31 to support the planks or the like of the platforms, but said sills project also in the opposite direction from said shafts and carry weights 33 which preferably consist of boxes filled with earth, gravel or the like. These weights are sufficiently heavy to normally swing the platforms 29 upwardly to the position of Fig. 2, and it will be observed that said weights operate within the openings 14. However, these weights are not sufficiently heavy to prevent easy downward swinging of the platforms by hand, when this is desired.

45 The planks or the like of the platforms 29 are of sufficient length to prevent the front wheels of a horse-drawn vehicle from leaving said platforms before the rear wheels move upon them, and the inner corners of these platforms are cut away as indicated at 34, so that as said platforms swing upwardly, they will not ordinarily strike the rearwardly projecting end of a wagon bed or other part of a vehicle. The edges of these cut-away portions or notches 34 however, disposed transversely of the base frame 10 when lowered, are preferably obliquely disposed as at 35 to prevent catching

thereof upon a wagon bed or the like in case they should strike the same. These edges and the inner edge portions of the platforms may well be bound with angle irons 36 although this is not essential.

When the platforms 29 are downwardly swung, their inner edges are in close proximity to the edges of the footboards 17 and the latch supporting bar 18, and they may be held in this downwardly swung position, by manually turning the latch 19 to the position of Fig. 1, in which it overlies both of said platforms. These platforms are swung downwardly by hand, that is either one or both of them are swung downwardly as occasion may demand, and while placing his weight upon one of the footboards 17 or the bar 18, the person operating the device swings the latch to the position of Fig. 1, and the action of the weights 33 tending to swing the platforms upwardly, will hold the latter against said latch with sufficient friction to hold the latter in operative position, against the action of the weight 23. After setting the device in this manner, assuming that the person who has set it, is the rider of a horse or the driver of a horse-drawn vehicle, who has dismounted to effect such setting, he will return to his vehicle or steed and drive on across the lowered platform or platforms. As soon as the weight of the horse or the horse-drawn vehicle is received by the aforesaid platform or platforms 29, depression of the latter will take place, relieving the frictional contact thereof with the latch 19, the result being that the weight 23 and cable 22 then immediately come into play to swing said latch to the released position of Fig. 2. Thus, as soon as the horse or the horse-drawn vehicle leaves the platform or platforms, the latter will be immediately raised under the influence of the weighted means 33 provided for that purpose. Hence, the entire device now remains in condition to prevent the passage of stock from one side of the fence or the like to the other and it is not necessary for the rider or driver to again dismount and go back to condition the device in this manner.

When one or both of the platforms 29 are to be held lowered, while a number of horse-back riders, horse-drawn vehicles, stock, etc. are passing thereover, the latch 19 may be held against release. For this purpose, I have shown a locking pin 37 insertible through appropriate openings 38 in the latch and the inner edges of the platforms. This locking pin is preferably carried by a short length of cable or chain 39 to prevent loss.

From the foregoing taken in connection with the accompanying drawings, it will be seen that I have provided a rather simple and inexpensive, yet an efficient and very desirable device for the purposes set forth, and while the details herein disclosed, may

be followed if desired, it is to be understood that the present disclosure is illustrative rather than limiting, in most respects. In this connection, it may be stated that while 5 two platforms are preferably employed in the construction of the device, it is of course possible to use such construction as to only embody one depressible platform, which would of course be of sufficient size to cover 10 the bars 13 when lowered.

I claim:

1. A combined stock guard and passway comprising a base having spaced members to prevent stock from walking thereover, a 15 platform pivotally mounted for downward swinging against the base, means exerting a force on said platform tending to swing it upwardly from the base, and means for holding said platform depressed while a vehicle or a horse-back rider moves onto the same, provision being made for automatically releasing said holding means while the vehicle or rider is thereon, whereby said platform may rise to its normal position 20 after passage thereover of the vehicle or rider.

2. A combined stock guard and passway comprising a base having spaced members to prevent stock from walking thereover, a 25 platform pivotally mounted for downward swinging against the base, means exerting a force on said platform tending to swing it upwardly from the base, and means releasable by maximum depression of said platform for holding it in a lowered position substantially horizontal but slightly above its maximum lowered position.

3. A combined stock guard and passway comprising a base having spaced members 40 to prevent stock from walking thereover, a platform pivotally mounted for downward swinging against the base, means exerting a force on said platform tending to swing it upwardly from the base, projectable and 45 retractable means for holding the platform in a substantially horizontal position slightly above its maximum lowered position, said holding means being freed by maximum depression of the platform, and 50 means operatively connected with said holding means for retracting it to released position upon freeing of said holding means.

4. A combined stock guard and passway comprising a base having spaced members 55 to prevent stock from walking thereover, a platform pivotally mounted for downward swinging against the base, means exerting a force on said platform tending to swing it upwardly from the base, a projectable 60 and retractable latch mounted on the base and projectable over a portion of the plat-

form to hold the latter in a substantially horizontal position slightly above its maximum lowered position, and means operatively connected with said latch for retracting it to released position when said latch is freed by maximum depression of the platform.

5. A combined stock guard and passway comprising a rectangular base frame, a plurality of transverse sills secured to the side bars of said base frame below the upper edges of the latter, a plurality of longitudinal spaced bars secured upon said sills and terminating short of the end bars of 75 said base frame, two downwardly and inwardly swingable platforms pivoted to the end portions of the base frame on transverse axes, weights carried by said platforms and operable in the spaces between 80 said end bars and the ends of said longitudinal bars to exert a raising force on the platforms, a transverse member secured upon said longitudinal bars and received between the platforms when the latter are lowered, 85 latch means mounted on said transverse member and projectable in opposite directions therefrom to engage the platforms and hold them against ascent when said platforms are substantially horizontal but 90 slightly above their maximum lowered positions, said latch means being freed by maximum depression of the platforms, and means connected operatively with said latch means for retracting the same to inoperative position upon freeing of said latch means.

6. A structure as specified in claim 5; said latch means consisting of a horizontal 100 latch bar and a vertical pivot connecting its central portion with said transverse member.

7. A structure as specified in claim 1; together with means for holding said platform-holding means against release when 105 desired.

8. In a combined stock guard and passway, a pair of inwardly and downwardly swingable self-raising platforms across which a horse drawn vehicle may pass when 110 lowered, said platforms having their inner corners formed with notches to lessen liability of striking the vehicle body as the platforms rise upon passing of the vehicle, said notches having oblique edges which 115 occupy inclined positions as said platforms rise, overcoming liability of catching on the vehicle if striking the same.

In testimony whereof I have hereunto affixed my signature.

FRANK FRNKA.
